Primary Examiner — April Rivas*Assistant Examiner* — Jillian Mazzola(74) Attorney, Agent, or Firm — Steven A. Nielsen; www.NielsenPatents.com(57) CLAIM

The ornamental design for a concealed knife holder, as shown and described.

DESCRIPTION

FIG. 1 is a front perspective view of a concealed knife holder showing the new ornamental design;

FIG. 2 is a top view thereof;

FIG. 3 is a bottom view thereof;

FIG. 4 is a left side view thereof;

FIG. 5 is a right side view thereof;

FIG. 6 is a back view thereof;

FIG. 7 is a front view thereof;

FIG. 8 is an exploded view thereof; and,

FIG. 9 is an exploded view thereof.

In FIG. 8 the broken lines are for the purpose of illustrating environment only and form no part of the claimed design.

1 Claim, 7 Drawing Sheets(56)
